UNITED STATES PATENT OFFICE.

MYRON R. RANDALL, OF WAUPACA, WISCONSIN.

AIR GUN OR RIFLE PLUNGER.

Application filed March 18, 1924. Serial No. 700,142.

To all whom it may concern:

Be it known that I, MYRON R. RANDALL, a citizen of the United States, residing at Waupaca, in the county of Waupaca and State of Wisconsin, have invented certain new and useful Improvements in Air Gun or Rifle Plungers, of which the following is a specification.

My invention relates to an air gun or rifle plunger.

This application is a continuation in part of my application for air gun plunger or piston, 680,133, filed December 12th, 1923, which last named application is a division 15 of my copending application for air gun or rifle, filed February 26th, 1924, Serial No. 621,401.

An important object of the invention is to provide an air gun or rifle plunger, which 20 is capable of obtaining the maximum compression, combined with long wear, and the minimum friction, whereby the plunger may have the maximum velocity.

A further object of the invention is to 25 provide a plunger of the above mentioned character which will operate with the maximum compression, for the maximum length of time, with the least lubrication.

A further object of the invention is to 30 provide a plunger of the above mentioned character, so constructed that the several packing rings may be properly applied thereto quickly and easily.

Other objects and advantages of the 35 invention will be apparent during the course of the following description.

In the accompanying drawings forming a part of this specification, and in which like numerals are employed to designate like 40 parts throughout the same,

Figure 1 is a side elevation of a plunger embodying my invention, the air chamber and associated elements being shown in section.

Figure 2 is a central longitudinal sectional view through the same,

Figure 3 is a perspective view of the elements constituting the packing,

Figure 4 is a side elevation of a piston ring, illustrating the customary manner of machining the same, and,

Figure 5 is a similar view of one of the rings upon my air gun or rifle plunger,

illustrating the manner of machining the same.

The efficiency of an air gun or rifle, particularly of the high power type, is dependent principally upon the efficiency of the plunger. This feature, has long been recognized by the workers in the air gun art, and the patents issued in that art, show clearly that numerous attempts have been made to increase the efficiency of the plunger, by producing high compression. In the air gun art, as far as I am aware, 65 it is the settled practice to employ a relatively soft packing upon the plunger of the air gun or rifle. This packing is in the form of leather, raw hide, or fibrous material, such as cotton or the like. This soft 70 packing is employed to produce the maximum compression, which can be obtained by its use, but there is a decided disadvantage, which is the creation of excessive friction. This friction cuts down the 75 velocity of the plunger, in turn impairing the efficiency of the gun. Further, this soft packing, readily distorts or expands, under the hammering action of the plunger, whereby the friction increases rapidly. As 80 a result of the use of the soft packing, excessive friction is always present in an air gun or rifle, and this requires frequent lubrication, in order that the gun may be shot with satisfactory results. In the high 85 powered English air gun, a leather packing is employed upon the plunger, and it is necessary to lubricate the gun frequently. I have found that after this gun has been shot for ten times, without lubrication, that 90 its efficiency will decrease materially. Further, the soft packing wears quickly, and hence will lose compression in use.

As above stated, as far as I am aware, it is the settled practice to employ this soft 95 packing upon the plunger of an air gun or rifle, and I do not believe that anyone has heretofore successfully used a hard radially resilient split packing ring, such as a cast iron packing ring, or a hard fibre 100 packing ring, upon the plunger of an air gun.

In my experiments in perfecting my air gun, my attention was directed to the marked inefficiency of the plunger of the air 105 gun and I attempted to overcome the same.

My first experiments were with the use of the soft packing, such as leather, and in this respect I followed the teachings of the prior air gun art. I became convinced that a wholly satisfactory packing could not be obtained by the use of soft packing.

I then turned to the use of a cast iron packing ring, which was split, and radially resilient. I placed this ring upon the plunger of my air gun, and tested the same, and found that the results were wholly unsatisfactory. The ring did not produce sufficient compression, and the friction was excessive, so that the velocity of the plunger was regarded to such an extent that the gun would not shoot with sufficient efficiency. In the first attempt to use the cast iron packing ring, I followed the settled practice of the art in connection with internal combustion engines, and I machined the cast iron ring down as accurately as the practice in the internal combustion engine art suggested. In the production of a metal packing ring for the piston of an internal combustion engine, it is customary to take the annular blank from which the ring is formed, and cut out a portion of the metal from such blank. This cut may be five-sixteenths of an inch, while this may vary, increasing with the increased diameter of the ring. The split ring is then compressed or drawn together so that the cut ends contact, and the compressed ring is then clamped upon an arbor. The periphery of the compressed ring is then machined down, and in following the settled practice in the internal combustion engine art, I machined the cast iron ring down to a slight oversize, about one one-thousandth of an inch oversize in diameter with respect to the diameter of the bore of the air chamber of the air gun. When the ring was taken off of the arbor, it was allowed to expand, and following the practice of the internal combustion engine art, the ends of the ring were filed down sufficiently whereby the ring could be compressed sufficiently to enter the bore of the air chamber.

In the experiments with my first ring, I machined the same to a slight oversize, as above stated, as is the settled practice in the internal combustion engine art, and found that this would not produce satisfactory results. The ring thus obtained produced excessive friction and insufficient compression. I found that the ring tended to contact at its free ends and at a point diametrically opposite such free ends.

Having thus met with failure in attempting to use the cast iron metal packing ring, in accordance with the teachings of the prior internal combustion engine art, I became very much discouraged and had almost concluded that such a ring could not be successively employed for the purpose de-

sired. However, I continued my experiments, and I finally conceived of the idea of machining the ring down very accurately, slightly below the diameter of the bore of the air chamber. I took an annular blank from which my ring was formed, and cut the same to split the ring. I have found that the cutting must be fine, and that better results are obtained by making the cut as fine, in width, as twenty-two one-thousandths of an inch. The blank thus cut or split was compressed so that its end contacted and the compressed blank was clamped to the arbor, of the lathe, and the periphery of the ring machined down very accurately, but slightly below the diameter of the bore of the air chamber. This machining was carried out to one four-thousandths of an inch in diameter of the ring with respect to the diameter of the bore of the air chamber. As a result of this accurate machining, below the diameter of the air chamber, which is the reverse of the settled practice in the internal combustion engine art, all difficulty was at once overcome, and a plunger obtained producing highly satisfactory results. I obtain high compression with the least friction, with the maximum velocity of the plunger. The ring contacted substantially evenly throughout its area, with the wall of the air chamber.

In the drawings, wherein for the purpose of illustration is shown a preferred embodiment of my invention, the numeral 5 designates the receiver of my air gun or rifle, as shown in my coending application Serial No. 621,421, hereinbefore referred to. Mounted to reciprocate within this carrier is the air chamber 6, which is of a relatively small diameter. This air chamber is provided at its forward end with a tubular socket 7, adapted to receive therein the reduced end or extension 8 of the barrel 9 of the rifle. A hard fibre washer 10 is mounted within the forward end of the air chamber, to take the impact from the plunger, and has an opening 11 in communication with the bore of the barrel. Compressible packing 12 is confined between the washer 10 and the forward end of the air chamber, as shown. As the air chamber is not claimed per se in the present application, it is thought that no further description of the same is deemed necessary.

The numeral 13 designates a plunger as a whole, which is used in my air gun or rifle, and this plunger embodies a cylindrical body portion 14, which is adapted to have a sliding fit within the air chamber 6. The body portion 14 has the forward end of a plunger rod 15 secured thereto, as shown. The body portion 14 carries a rear annular flange 16, provided with annular grooves 17, carrying lubricating rings 18, which may be made of felt, or any other suitable

material. The body portion 14 is provided with a forwardly extending portion 19, which is diametrically reduced or contracted, and is adapted for the reception of the 5 packing rings of the plunger. The contracted portion 19 is cylindrical and is integral with the body portion 14.

I have found that the packing rings, to be described, are of great importance, as I 10 have been able to obtain the maximum compression, the least friction, the high velocity of the plunger, and the minimum use of lubrication.

The numerals 20 and 21, designate rings 15 or carriers, which are integral, that is not split, and formed of metal. These rings or carriers are L-shaped in cross section and are slipped upon the reduced portion 19 of the plunger, over the forward end thereof. 20 The carrier 20 supports the split packing ring 22, preferably formed of cast iron, while the carrier 21 supports the split packing ring 23, preferably formed of hard fibre, namely, hard vulcanized fibre, or other 25 non-metallic material, possessing similar characteristics. It might be stated at this point that, by the use of the terms "hard relatively non-compressible material" in the claims, I mean such a material having the 30 characteristics of hard metal, such as cast iron, or hard vulcanized fibre, as distinguished from a packing which is relatively soft and compressible, and will distort under action, such as leather, raw hide, and 35 other fibrous or cotton packing. Arranged forwardly of the carrier 20 is a solid or integral packing ring 24, which is not split, and preferably formed of hard vulcanized fibre, although any other suitable non-metallic 40 material, having like properties may be employed. The several rings are retained in place upon the reduced portion 19 of the plunger by means of a head or cap 25, secured to the reduced portion 19 by means 45 of a screw 26 or the like. The precise construction of the plunger and its packing means are preferred, although changes may be resorted to.

I provide the solid non-split ring 24, 50 formed of fibre, as the same constitutes a guide means for the plunger within the air chamber, and the fibre will slide within the air chamber with the least friction. I have also found that satisfactory results are 55 obtainable by using the split ring 22 of cast iron and the split ring 23 of hard vulcanized fibre. The cast iron packing ring tends to produce better compression, but there is 60 a tendency to develop friction, while the split fibre ring does not tend to produce quite as much compression, but less friction. I have found that highly advantageous 65 results are obtainable by employing the two split packing rings, one of cast iron and the other of fibre, and having their combined

cross-sectional areas equal about to that of one packing ring, and hence I obtain a combination of the advantages of both types of packing rings.

By the use of the ring carriers, I am enabled to use two or more rings, without having undue friction upon the side walls of the rings, thus leaving the rings free to expand, and properly fit the inner wall of the air chamber. Further, the carriers, with the reduced portion or extension of the plunger, enable these rings to be slipped into position, without radial expansion. If a ring of the small diameter of these rings, 70 were attempted to be sprung in place upon the plunger, they would either break, or become permanently distorted.

Experiments which I have made, show 75 that satisfactory results can be obtained by equipping the plunger of an air gun with a single split cast iron ring, and also that satisfactory results can be obtained by equipping the plunger with a single split 80 vulcanized hard fibre ring. The difference 85 in the use of the two rings, is slight, and I believe that there is a slight advantage in using the hard fibre ring. The hard fibre ring is produced in precisely the same manner as the metal ring, and is split, compressed, and then accurately machined to a 90 diameter slightly below the fit of the diameter of the air chamber, to about one four-thousandth of an inch.

In Figure 4, I have illustrated a piston 95 ring 27, as ordinarily employed in an internal combustion engine, and the ring is machined with a diameter slightly over the diameter of the bore of the cylinder, which cylinder diameter is indicated at 28. Figure 5 illustrates the manner of producing 100 the rings for my air gun or rifle. The ring is indicated at 29, which ring may be either a split cast iron ring or a split hard vulcanized fibre ring. The ring is machined slightly 105 below the diameter of the bore of the air chamber, and 30 designates the bore of the air chamber. As I have heretofore stated, 110 highly satisfactory results have been obtained by machining the rings, for use in my air gun, to a diameter of one four-thousandth of an inch beneath the diameter of the bore of the air chamber. The rings must be machined thus accurately, and the machining must be below the diameter of 115 the bore of the air chamber. This produces high compression with the minimum friction.

Experiments which I have conducted, 120 show me that with the best of the common type of plungers in air guns, embodying the soft packing, it is necessary to oil the chamber about every twenty-five shots, to obtain a uniform velocity, at anywhere near the maximum, and it is frequently necessary 125 to oil the air chamber, particularly in 130

a high powered air gun, after the gun is fired for ten shots. With my gun, having a plunger equipped with the hard rings, I have found that the gun will fire with uniform velocity for approximately two hundred shots or more, for each lubrication of the air chamber. I have found that my gun develops unusual power, and will drive a twenty-two bullet through a board from three-fourths to seven-eighths of an inch thick, causing the bullet to strike upon a hard metal plate and flatten out.

It is to be understood that the form of my invention herewith shown and described is to be taken as a preferred embodiment of the same, and that various changes in the shape, size, and arrangement of parts may be resorted to, without departing from the spirit of my invention, or the scope of the subjoined claims.

Having thus described my invention, I claim:

1. An air gun or rifle plunger, a solid hard fibre ring mounted thereon to serve as guide means, a split resilient metallic packing ring carried by the plunger at the

rear of the solid ring, and a split hard fibre packing ring carried by the plunger at the rear of the metallic ring.

2. An air gun or rifle plunger, a split radially resilient metallic packing ring carried by the plunger, and a split radially resilient hard fibre packing ring carried by the plunger.

3. An air gun or rifle plunger, and a split radially resilient packing ring carried by the plunger, said packing ring being formed of a hard relatively non-compressible material, said packing ring being machined slightly below the diameter of the bore of the air chamber.

4. An air gun or rifle plunger, and a split radially resilient packing ring carried by the plunger, said packing ring being formed of a hard relatively non-compressible material, said packing ring being machined slightly below the diameter of the bore of the air chamber, said split being fine whereby the ring will produce the least friction by sliding contact with the air chamber.

In testimony whereof I affix my signature.

MYRON R. RANDALL.
